UNITED STATES PATENT OFFICE.

JOSEPH L. VOTAW AND MERTON J. LA VANWAY, OF STIGLER, OKLAHOMA.

COMBINED CLAMP AND THIMBLE.

Specification of Letters Patent.

Patented Nov. 25, 1919.

1,322,849.

Application filed April 12, 1919. Serial No. 289,492.

To all whom it may concern:

Be it known that we, JOSEPH L. VOTAW and MERTON J. LA VANWAY, citizens of the United States, residing at Stigler, in the county of Haskell and State of Oklahoma, have invented certain new and useful Improvements in Combined Clamps and Thimbles, of which the following is a specification, reference being had to the accompanying drawings.

This invention relates to thimbles such as are used for forming a bight in a rope or cable.

These thimbles are ordinarily approximately ovoidal in form and transversely semi-circular to receive the bend of the rope or cable, and the two portions of the rope or cable on each side of the thimble are held in engagement with the thimble by a wrapping of wire or cord.

The general object of this invention is to provide a combined rope clamp and thimble so constructed that a bight may be readily formed, further so constructed that the rope or cable will be held firmly within the thimble and prevent it from accidental detachment therefrom, and further so constructed that the thimble may be clamped tightly upon the rope by means of bolts, thus preventing any chance of the rope slipping through the thimble without the necessity of using a wrapping of wire or cord around the two ends of the rope or cable.

Still another object is to provide a construction of this kind formed of one piece of material.

Other objects will appear in the course of the following description.

Our invention is illustrated in the accompanying drawings, wherein:

Figure 1 is a face view of a blank from which the clamp and thimble are made;

Fig. 2 is a perspective view showing the clamp and thimble in use;

Fig. 3 is a section on the line 3—3 of Fig. 2; and

Fig. 4 is a section on the line 4—4 of Fig. 2.

Referring to Fig. 1, it will be seen that the blank from which this improved thimble is constructed, and which blank is designated A, is formed to provide terminal portions 10 and 11 which extend in opposite directions relative to each other, and an intermediate portion 12 which connects the terminal portions. The terminal portions are

provided with perforations 13 for the passage of clamping bolts.

This blank is bent to the shape shown in Figs. 2 and 3, that is the intermediate portion 12 of the blank is bent upon itself in approximately horseshoe shape so that the terminal ends 11 overlap each other and are disposed in superposed relation, with the perforations 13 in alinement. The intermediate portion 12 of the blank is transversely curved so as to form a rope channel 14. This rope channel 14 extends down to the edge of the terminal portion 10 and to the edge of the terminal portion 11. When the blank is bent to form a complete thimble, the rope channel where it intersects the terminal portion 10 opens upon the side faces of the terminal portions. Then the rope channel is twisted in a slight spiral so that where the intermediate portion 12 meets the terminal portion 11, the rope channel faces toward the terminal portion 10. Thus, at the meeting points of the rope channel with each terminal portion, the rope channel faces toward the opposite terminal portion. The outer margin of each terminal portion 10 and 11 is outwardly bent, as at 15, to form a clamping jaw which overlaps the rope channel of the other terminal portion so that when bolts 16 are disposed through the perforations 13, the two clamps formed by the terminal portions 10 and 11 will be drawn tightly against each other and will bind the rope between them.

It will be seen that the middle portion of the bight of the rope thus formed is supported in the rope channel with the flange of the rope channel extending equally on both sides of the rope so that there is no danger of the rope becoming detached from this channel. The rope is also held from any longitudinal movement in the channel by the clamping action of the terminal members.

A thimble of the character described is adapted to be used in any usual or ordinary manner and is suitable for all purposes for which an ordinary thimble is suited. It will release strain on the rope without any chance of the rope being cut by the wire wrappings or cord wrappings usually used and, of course, entirely eliminates the chance of the wrappings rusting out or becoming broken or loosened. This construction further provides for a ready removal of the thimble and clamp whenever necessary.

While a particular form for this clamp has

been illustrated, yet it is obvious that many changes might be made in the details of construction without departing from the spirit of the invention.

5. We claim:—

1. A combined thimble and rope clamp comprising a body having an intermediate portion bent to form a rope channel, end portions extending at right angles to the intermediate portions and formed to provide oppositely disposed rope clamps forming continuations of said channel, and means extending through said end portions whereby they may be forced toward each other.
10. 2. A combined thimble and rope clamp comprising a body having an intermediate, transversely curved rope receiving channel, the ends of the body being formed with transversely extending terminal portions, the
15. opposite extremities of each terminal being concavely curved to form at one end a continuation of the rope channel and at the other end a clamping jaw, said terminal portions being disposed in confronting relation
20. to each other whereby the jaw of one terminal portion will be opposed to the rope channel of the other terminal portion, and clamping bolts passing through said terminal portions whereby the terminal portions may be urged toward each other to clamp a rope within said channel.
25. 3. A rope clamp comprising a blank of

metal formed to provide an intermediate, longitudinally extending portion, and oppositely directed terminal portions, the blank 35 being bent in the shape of a horseshoe with the terminal portions facing and opposed to each other, the intermediate portion of the blank being formed to provide a transversely extending rope receiving channel, one end 40 of each terminal portion being formed with a continuation of said rope receiving channel and its opposite end with an outwardly curved jaw, the terminal portions between the channel and jaw having perforations for 45 the passage of clamping bolts.

4. As an article of manufacture, a combined rope thimble and clamp having a body portion formed to provide a horseshoe-shaped, transversely curved channel, the ends 50 of the body portion being formed to provide opposed, transversely curved, rope clamps, and clamping bolts passing through said terminal portions whereby they may be urged toward each other to clamp the ends 55 of a rope between them.

In testimony whereof we hereunto affix our signatures in the presence of two witnesses.

JOSEPH L. VOTAW.
MERTON J. LA VANWAY.
